Inventor:
James F. Lyons,
By his attorney;
Parker S. Gooding.

UNITED STATES PATENT OFFICE.

JAMES F. LYONS, OF SOMERVILLE, MASSACHUSETTS.

SPIRIT-LEVEL.

1,114,277.

Specification of Letters Patent. Patented Oct. 20, 1914.

Application filed January 16, 1913. Serial No. 742,493.

To all whom it may concern:

Be it known that I, JAMES F. LYONS, a citizen of the United States, residing at 10 Line street, Somerville, in the county of Middlesex and State of Massachusetts, have invented a new Spirit-Level, of which the following is a specification.

This invention relates to improvements in spirit-levels and has for its object to provide a level in which the angle of the spirit glass may be varied relatively to the stock of said level and secured in the position desired.

The invention consists in the combination and arrangement of parts whereby the above object and certain other objects hereinafter appearing may be attained, as set forth in the following specification and particularly pointed out in the claims.

Referring to the drawings: Figure 1 is a side elevation of a level with two devices embodying my invention shown in connection therewith, portions of the stock of said level being broken away to save space in the drawings. Fig. 2 is an enlarged sectional elevation taken on line 2—2 of Fig. 1 and viewed in the direction of the arrows on said line. Fig. 3 is a section taken on line 3—3 of Fig. 2 as viewed in the direction of the arrows on said line. Fig. 4 illustrates in detail the semicircular members constituting the ring upon which the spirit glass casing is arranged to revolve. Fig. 5 is a detail view of one section of the cylindrical bushing.

Like numerals refer to like parts throughout the several views of the drawings.

In the drawings, 6 is the stock which may be of any suitable material, such as mahogany or the like and provided with a plurality of holes 7 extending laterally therethrough. In each of said holes 7 is arranged a bushing 8 formed in two cylindrical sections 9 and 10, the outer ends 11 of said bushings alining with the respective faces of said stock 6.

A ring 12 consisting of two semicircular members 13 and 14 is arranged within the hole 7 intermediate the adjacent ends 15 of said bushing sections, each of said sections contacting with said ring. The diameter of the hole through said ring is substantially smaller than the internal diameter of said bushings, while the outside diameter of said ring is substantially equal to the outside diameter of said bushings, or in other words,

adapted to fit the hole 7. A spirit glass 16, which is of the usual construction substantially filled with spirits with the exception of a very small part thereof or bubble of air, is arranged in said bushing within a metal casing 17, said casing being cut away at 18 to expose the central portion of said spirit glass.

The casing 17 is provided with slots 19 at opposite ends extending longitudinally thereof adapted to receive opposite portions of said ring 12, thereby retaining said casing within the bushing 8 and permitting said casing to be angularly adjusted therein, said casing being slightly shorter than the internal diameter of said bushing and the distance between the inner ends of said slots being slightly less than the internal diameter of the ring 12, thereby permitting said casing to be freely adjusted angularly within said ring or at least so that there will be no binding between said casing and said bushing and the inner periphery of said ring. Means are provided for securing said casing to the ring 12 at a predetermined angle relatively to the stock 6, said means consisting preferably of screws 20 arranged adjacent the ends of said casing and laterally thereof in holes 21 in said casing and having screw-threaded engagement with nuts 22, which substantially fit the portions of the ends of said casing between the face 24 of the ring 12 and the adjacent inner surface of said casing. The inner ends of said screws engage the face of the ring adjacent said nut and as said screws are rotated said nuts will be forced against the inner walls of said casing and the ends 23 of said screws more firmly engage said face 24 of said ring.

As the casing 17 is secured to the ring to prevent said casing from rotating, it is essential that said ring be prevented from rotating relatively to the stock, therefore the sections of said ring are provided with notches 25 which are adapted to be engaged by tongues 26 formed upon one of the sections of the bushing 8, preferably the section 9 and projecting laterally from the edge 15 thereof, while said bushing is in turn secured to the stock 6 by screws 27. The section 10 of said bushing is likewise secured by screws 27 to the stock 6 thus firmly binding and securing said ring in its position within the hole 7.

In assembling the device one of the sections of the bushing 8, preferably 10, is

placed within the hole 7 and secured therein by screws 27. The two sections of the ring 12 are then assembled, one in each of the grooves 19 in the ends of the casing 17 after which said casing and said ring is placed in the hole 7 against the end 15 of the sections 10 of said bushing. The other section 9 is then inserted in the hole 7 from the opposite end with tongues 26 engaging the notches 25 and secured in such a position by the screws 27.

With a plurality of devices hereinbefore described shown attached to a single stock it will be readily seen that the spirit glass casings may be adjusted at various angles relatively to said stock to permit said stock to be used to plumb or level certain surfaces or to set surfaces at any predetermined angle relatively to a horizontal or vertical plane.

Having thus described my invention what I claim and desire by Letters Patent to secure is:

1. In a device of the class described the combination of a stock provided with a hole extending laterally therethrough, a bushing formed in two cylindrical sections arranged in said hole, and a ring consisting of a pair of semicircular members arranged in said hole intermediate the adjacent ends of said bushing sections, a spirit glass, a casing for said spirit glass adapted to engage and to be angularly adjusted in said ring, and means adapted to secure said casing at a predetermined angle relatively to said stock.

2. In a device of the class described the combination of a stock provided with a hole extending laterally therethrough, a bushing

arranged in said hole and formed in two sections each secured to said stock, a ring 40 consisting of a pair of semicircular members interposed between the adjacent ends of said sections, means on said bushing adapted to engage said ring and lock the same against displacement, a spirit glass, a casing 45 adapted to contain said glass, said casing having longitudinally arranged slots at opposite ends thereof adapted to receive opposite portions of said ring and permit said casing to be angularly adjusted therein, and 50 means contained in said casing adapted to engage said ring and lock the same at a predetermined angle relatively to said stock.

3. In a device of the class described the combination of a stock provided with a hole 55 extending laterally therethrough, a ring arranged in said hole and secured to said stock, a spirit glass, a tube arranged to be angularly adjusted within said stock and adapted to contain said spirit glass, said 60 tube having longitudinally arranged slots at opposite ends thereof, adapted to receive said ring, and guide said tube during the angular adjustments thereof, nuts arranged in the ends of said tube adjacent said slots 65 respectively adapted to substantially fit that portion of said tube, and screws having screw-threaded engagement with said nuts and adapted to engage said ring and lock 70 said casing at a predetermined angle relatively to said stock.

JAMES F. LYONS.
